US0D1069716S

(12) **United States Design Patent** (10) Patent No.: **US D1,069,716 S**
(45) Date of Patent: ** Apr. 8, 2025

(54) **CONNECTOR**

(71) Applicant: **Molex, LLC**, Lisle, IL (US)

(72) Inventors: **KrishnaPrasad Darbal Somanath**, Bangalore (IN); **Gautam Sharma**, Patna (IN); **Harsha Thyagaraj**, Bangalore (IN); **Sreenath A**, Kerala (IN); **Shivasharan Basavaraj Mahajanshetty**, Bangalore (IN)

(73) Assignee: **Molex, LLC**, Lisle, IL (US)

(**) Term: **15 Years**

(21) Appl. No.: **29/891,424**

(22) Filed: **May 5, 2023**

(51) LOC (15) Cl. **13-03**

(52) U.S. Cl.

USPC **D13/133**

(58) Field of Classification Search

USPC ... D13/133, 101, 123, 146, 147, 153, 137.1, D13/149; D14/435.1, 433

CLAIM

The ornamental design for a connector as shown and described.

DESCRIPTION

FIG. 1 is a front top perspective view of a connector showing our new design;

FIG. 2 is a front bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The even-length broken line portion of the figure drawings depict portions of the connector that form no part of the claimed design.

1 Claim, 8 Drawing Sheets
